UNITED STATES PATENT OFFICE.

HENRY L. PITMAN, OF ELIZABETH, NEW JERSEY, ASSIGNEE TO UNDERWOOD COMPUTING MACHINE COMPANY, OF NEW YORK, N. Y., A CORPORATION OF NEW YORK.

COMBINED TYPEWRITING AND COMPUTING MACHINE.

1,393,244.

Specification of Letters Patent. Patented Oct. 11, 1921:

Application filed April 11, 1918. Serial No. 227,976.

To all whom it may concern:

Be it known that I, HENRY L. PITMAN, a citizen of the United States, residing in Elizabeth, in the county of Union and

5 State of New Jersey, have invented certain new and useful Improvements in Combined Typewriting and Computing Machines, of which the following is a specification.

This invention relates to typewriting and 10 computing machines, and particularly to those in which a master-wheel is employed.

The invention is herein disclosed as applied to the well-known Underwood addendograph, in which a key-driven master-wheel is mounted upon the stationary frame-work, while the computing wheels travel.

The typewriter carriage is returned automatically when the last digit of a number is computed or when the line is completed; 20 and it has been the practice when employing carriage-returning mechanism for the operative to actuate the final type-key with unusual speed, and then to wait until the carriage returns.

25 This mode of operation is a burden upon the operative. In case he fails to be alert, the master-wheel may happen to be in an abnormal position (due to a numeral key being partially depressed while the carriage is returning), so that a collision may occur between the teeth of the computing wheels and the teeth of the master-wheel. One object of the invention is to avoid this difficulty. To this end, the carriage is prevented 35 from returning during the actuation of the computing mechanism by connecting the numeral keys with the carriage-returning mechanism in such a manner that after typing the final digit the started carriage-returning mechanism will be held in abeyance until the end of the up-stroke of the numeral key.

It has been customary for the operative to watch the returning carriage so as not to depress a tabulator-key until the carriage has finished returning. This is necessary in order to avoid a collision between the tabulating stops and the column dogs.

To avoid this burden upon the operative, I provide a member which prevents the depression of any decimal-tabulator-key when the carriage is returning.

It is customary to arrange the wheels in denominational groups, each group separated from the next by one letter-space, so that 55 a punctuation mark may be typed upon the

work-sheet between the groups. When a punctuation space is at the computing point the master-wheel is not in mesh with any computing wheel.

It may happen that the operative will inadvertently depress a numeral key when a punctuation space is at the computing point, thereby causing a digit to be typed upon the work-sheet without any computation taking place, and other errors may follow.

60 I have provided improved mechanism for locking the numeral keys when a punctuation space is at the computing point, and for controlling said lock directly from the totalizer. It will not be necessary for the operative to make separate readjustments of the locking devices whenever a totalizer is shifted along the carriage.

65 The totalizer has cams arranged in conformity with the punctuation spaces between dial wheels, so that said cams will be effective to actuate the numeral-key-locking mechanism whenever a punctuation space is at the computing point.

70 I overcome clatter and wear by providing means whereby this key-locking mechanism may be held in co-operative position with the cams at the rear of the totalizers during the letter-feeding movements of the carriage, and may be withdrawn from co-operative position with said cams during the return of the carriage.

75 The carriage-returning mechanism is so connected with this key-locking mechanism that the part thereof which normally lies in the path of said cams will be moved out of such path during the return of the carriage.

80 It has been the practice in machines of this type to employ an electric motor for returning the carriage. I have improved the construction of the switch for closing the circuit through the motor and of the connections between the switch and the carriage-returning mechanism, so that fine adjustments between the switch-closing device and the rest of the carriage-returning mechanism will not be required. The switch and its connections with the carriage-returning mechanism are such that the switch may be 85 easily removed from the machine for repairs, without the use of tools, and without disassembling the connections with the carriage-returning mechanism or altering the 90 adjustments of the latter.

Other features and advantages will hereinafter appear.

In the accompanying drawings,

Figure 1 is a sectional side elevation of an Underwood addendograph, showing the invention applied thereto.

Fig. 2 is a fragmentary sectional side view of the right-hand margin stop and a portion of the adjacent mechanism.

Fig. 3 is a sectional front elevation of the machine with parts omitted for clearness and parts broken away to show the underlying structure.

Fig. 4 is a skeleton perspective view of portions of the machine, showing the invention applied thereto.

Numeral keys 10 and character keys 11 (Fig. 1), mounted on key-levers 12, are connected to rock bell-cranks 13 connected to swing types 14 fast on type-bars 15 upwardly and rearwardly against a platen 16 revolvably mounted on a typewriter carriage 17, which is adapted to travel laterally on rails 18, 19, mounted at the front and rear of the platen.

To cause the typewriter carriage 17 to move step by step, each of the type-bars 15 is provided with a heel 20 which thrusts rearwardly a universal bar 21 (Fig. 1), to actuate an escapement mechanism, indicated in general at 22 (Fig. 3), usually provided with a pinion 23 which co-acts with a rack-bar 24 (Figs. 1 and 3), pivoted at 25 to the typewriter carriage 17, which is driven by a spring drum 26 and a draw band 27 (Fig. 3).

A left marginal stop 30 (Figs. 1 and 4) is adjustable on a frame 31 supported for swinging movement on a shaft 28 mounted on the frame work and has an index 32 for use with a scale 33. A spring 29 normally holds frame 31 in raised position.

A right adjustable marginal stop 34 (Figs. 2 and 4) has an index 35 to co-act with the scale 33.

Each numeral key-lever 12 has attached thereto a valuating member 40 (Figs. 1 and 3), to rock a universal bail 41 an amount directly proportional to the digital value of the key.

This universal bail 41 is operatively connected with a non-traveling master-wheel 42 (Fig. 1). A plate 43 forming part of the typewriter carriage 17, carries, adjustably positioned thereon totalizers 44 having computing wheels 45 to mesh with the master-wheel. A driving gear 46 for said master-wheel is actuated by mechanism partially illustrated at Fig. 1, and controlled by the universal bail 41, as more fully illustrated and described in my co-pending application, Serial No. 24,390, filed April 28, 1915. (Now Patent No. 1,308,506, dated July 1, 1919).

The decimal-tabulating mechanism includes keys 50 (Fig. 1) attached to levers 51

pivoted on a fulcrum 52. The rear ends of said levers raise denominational stops 53 into the path of column stops or dogs 54 on a rack-bar 55 on the carriage 17.

To start the carriage-returning mechanism at the end of a computation, an extension 60 (Figs. 1 and 4) on the carriage 17 trips a latch 68, which normally holds the carriage-returning mechanism silenced. This is accomplished by placing the left marginal stop 30 so that a pivoted cam 61 thereon will be actuated by said extension to swing the frame 31 on which said stop 30 is mounted and depress a link 62, the upper end of which is pivoted to a bracket 31^a and the lower end of which is connected to swing a lever 63, pivoted on a fixed part of the frame, to trip said latch which is formed on the forward end of a thrust bar 65. It will be understood that shaft 28 is not affected by a rocking or swinging movement of frame 31. When the latch 68 is thus tripped, a spring 67 will actuate the thrust bar 65 rearwardly to swing a transverse rock-shaft 71, which, through the intermediary of connections indicated in general at 72, closes a clutch 73 to connect the carriage 17 with the motor-driven mechanism 74 which has a pinion 75 meshing with a rack 76 on the carriage, thereby driving the carriage back.

To arrest the returning carriage, the driving clutch 73 is opened by the extension 60 striking against a cam 88 (Fig. 4) mounted on an arm 89 splined on shaft 28 and associated with the right marginal stop 34 and 100 embraced thereby, to actuate connections indicated in general at 91, which open the clutch, thereby disconnecting the carriage. It will be understood that arm 89 will accompany stop 34 when the latter is 105 moved to different positions along scale 33. Depression of arm 89, due to engagement of cam 88 by extension 60, will rock shaft 28, and this movement will be transmitted to shaft 39 by means of arm 36, link 37 and 110 arm 38. From shaft 39 motion is transmitted by arm 47, link 48 and a relatively long link 49, slidably mounted at one end on a pin 49^a, to an arm 57 fixed on a shaft 58 at the rear of the machine. Another arm 59 115 on shaft 58 carries at its free end a ball extending into a groove 75^a on a sliding collar carrying gear 75, and serves to control clutch 73. To prevent overthrow of the carriage, the right marginal stop is provided 120 with an extension 95 against which the carriage strikes.

To close the electric circuit through the motor 86 (Fig. 1), it is connected with an outside source of power by electric conductors 107 (Figs. 1 and 4) connected with a normally open switch 108 provided with contacts 109, 110, one of which is continually urged by a spring 111 to close the switch, but is held out of engagement with the other 130

contact by a mechanism connected to and controlled by the rock-shaft 71 of the carriage-returning mechanism in such a manner that said switch will be closed and 5 opened simultaneously with the closing and opening of the clutch 73.

To hold the switch contacts 109, 110, separated against the tension of the spring 111, there is provided a plunger 112 (Figs.

- 10 1 and 4), one end of which bears against the contact 109 and extends and is guided through an aperture in a base 113 of the switch. To withdraw the plunger 112 from the upper contact 109 to close the 15 switch, the lower end of the plunger is pivoted to the rear end of a lever 115 fulcrumed on a bracket 116 (Fig. 1) on the framework. The other end of said lever has a pin-and-slot connection 117 (Figs. 1 20 and 4) with a rearwardly-extending arm 118 fast on the rock-shaft 71 of the carriage-returning mechanism, so that when said rock-shaft is actuated by the carriage 17, when it reaches the left marginal stop 30, 25 the plunger 112 will be withdrawn from said contact 109, which will then be swung against the contact 110, by its spring 111, thereby closing the circuit through the motor to actuate the driving mechanism 74 to 30 return the carriage.

To open the switch 108 and break the circuit through the motor 86 when the carriage 17 is returned, the rock-shaft 71 is swung in an opposite direction at the actuation of the right marginal stop 34 by the carriage, through the intermediary of the connections 91 and 72, to swing the lever 115 and raise the switch plunger 112 and therewith the upper switch contact 109 35 against the tension of its spring 111 and the spring 67, to separate said contacts 109, 110, thereby opening the switch 108, at which time the actuation by the motor of the driving mechanism 74 will cease simultaneously with the opening of the clutch 73.

It will be noted that with this construction, the switch 108 may easily be removed from the machine for repairs or replacement and may easily be returned to the machine 50 without in any way affecting the adjustments of the carriage-returning mechanism. The switch may be loosened from its anchorage, by removing the thumb screws 120, (Fig. 1) and lifting it off the plunger 112, 55 which holds the contacts apart, and may easily be replaced by guiding said plunger through the aperture in the base 113 of the switch when replacing the switch.

It will also be noted that fine relative 60 adjustments between the connections for controlling the switch 108 (Figs. 1 and 4) and the connections for controlling the clutch 73 will not be required, since the parts which are actuated to close the clutch 65 may move given amounts regardless of the

amount of motion required to close the switch, so long as sufficient downward motion of the switch-controlling plunger 112 is provided; any excessive motion of said plunger being idle. It will also be seen 70 that the required amount of downward motion of said plunger 112 (Fig. 4) is small, since the plunger bears against the contact 109 at a point near its pivot.

It will be noted that the electric switch is 75 accessibly located at the rear of, and without, the framework, where it in no way interferes with the free manipulation of the machine.

When a numeral key 10 is in a partially 80 depressed position, the master-wheel 42 may be in an abnormal position and out of meshing relation with those of the computing wheels 45 which are out of mesh with the master-wheel, so that the teeth of the master-wheel 42 will lie in the path of travel of the teeth of the computing wheels 45 when the latter are in a normal position.

If any of the computing wheels 45 are at this time beyond the master-wheel 42 85 and the carriage 17 is returned, the teeth of said wheels, being in a colliding position, will arrest the return of said carriage when a collision occurs between the teeth of the computing wheels and the teeth of the master-wheel, thereby causing said teeth to break or causing other wreckage of the machine, besides subjecting the parts of the machine to undue strain, since the motor will continue to drive, the switch 108 being 90 closed when a collision occurs.

When the computing wheels 45 and the master-wheel 42 are in a colliding position, the carriage 17 is prevented from returning to avoid collision of the teeth of the computing-wheels 45 with the teeth of the master-wheel 42 by locking the returning mechanism.

For this purpose, each numeral key-lever 12 (Figs. 1, 3 and 4) is provided with a 110 dependent plunger 125 pivoted on the numeral key-levers and guided at its lower end in a slot 126 formed in a transverse angle bar 127 of cross-sectional L-shape, to hold said plungers against forward and rearward displacement. The lower end of each of the plungers 125 is arranged to pass between a pair of adjacent pendants 128 pivotally mounted at 129 on said L-shaped bar 127, one pair of pendants 128 being provided for 115 each numeral key plunger 125.

The pendants 128 are spaced along the transverse bar 127 relatively to the thickness of the plungers 125, so that only one plunger at a time may pass between any 125 pair of pendants, as seen at Fig. 3. All the lost-motion between the entire train of pendants will be taken up when a single plunger 125 passes therebetween, so that no other key plunger 125 may pass there- 130

between, the pendants being confined at each end of the train by pins 130 (Figs. 1, 3 and 4) fast on said L-shaped bar 127, thus preventing the simultaneous actuation of two 5 or more numeral keys.

This mechanism for preventing the simultaneous actuation of two or more numeral keys is adapted to prevent the actuation of the carriage-returning mechanism during 10 the actuation of a numeral key.

A vertically-disposed member 132 (Figs. 1, 3 and 4), in the form of a bar or plunger, is connected to be actuated by the carriage-returning mechanism, and, when so actuated, passes between one of a pair of pendants 128 and an adjacent pendant 133, similar to the pendants 128, said pendant 133 being one of said train of pendants.

It will be seen that when a numeral key 20 10 is depressed and all the lost-motion between said pendants 128 and 133 taken up by the associated numeral key plunger 125, the vertically-disposed bar 132 will be prevented from passing between its pendants 25 and thereby prevent the actuation of the carriage-returning mechanism with which it is connected.

The connections for actuating the vertically-disposed bar 132 when the carriage 30 17 reaches the end of its leftward travel include a forwardly-extending arm 134 (Figs. 1 and 4) fast on the rock-shaft 71 of the carriage-returning mechanism, which is adapted to be swung downwardly at the 35 actuation of the left marginal stop 30 when the carriage 17 reaches the end of a line and swings the rock-shaft 71.

It will be seen that when the carriage extension 60 reaches the left marginal stop 30, 40 when a numeral key is in depressed position, the vertically-disposed bar 132 is locked against actuation, being held against passing between its pendants 128, 133. The release of the latch 68 when the carriage 45 reaches the left marginal stop 30 will, however, not be prevented by the failure of said bar to pass between its pendants, but the switch 108 and clutch 73 will not be closed. The return mechanism of the carriage will 50 thus be held in abeyance until the completion of the up-stroke of the numeral key, when its plunger 125 will move out of engagement with the pendants 128, and the vertical bar 132 will enter between its pendants 128, 133, after which the switch and clutch will be closed and the carriage will 55 be automatically returned.

When the carriage has reached its initial position, the parts of the carriage-returning 60 mechanism will be moved in an opposite direction through the intermediary of the connections 91 and 72, to restore said parts and the latch 68 to their normal positions and to open the switch 108 and clutch 73, thereby 65 silencing the carriage-returning mechanism.

When a decimal-tabulator-key 50 is depressed, before the carriage 17 has reached the end of its travel, a tabulator-stop 53 will rise into the path of a dog 54 on the carriage, causing a collision between said 70 stop and dog, thereby preventing the carriage from reaching its initial position and preventing the opening of the switch 108 and the clutch 73. Under these conditions, the motor 86 will continue in its 75 efforts to drive the carriage 17 and may wreck the machine. In case the parts are of sufficient strength to avoid wreckage, the carriage 17 and totalizer 44 thereon will not be denominationally positioned in accord with the denominational value of the 80 actuated tabulator-key 50.

To prevent any tabulator-key 50 from being depressed during a return movement of the carriage 17, there is provided a mechanism, 85 substantially as illustrated and described in my co-pending application, Serial No. 181,460, filed July 19, 1917, (now Patent No. 1,349,386 dated August 10, 1920) co-acting with the mechanism for locking the 90 carriage against returning during the actuation of a numeral key. The mechanism disclosed in said application includes a lever 147 (Figs. 1 and 4) common to the key-levers 51 of the tabulator-keys and placed 95 to be actuated thereby at the depression of a tabulator-key. Said lever 147 is connected to swing an arm 150 into and out of engagement with said pendants 128. It will be seen that when the lost-motion between said pendants 128 is taken up by the 100 vertical bar 132 of the carriage-returning mechanism, the decimal-tabulator-keys 50 will be locked against actuation, since the arm 150 connected with said keys 50 cannot 105 be actuated to pass between said pendants.

In case the left marginal stop 30 is misplaced, so as to lie within the zone of movement of the typewriter carriage 17 in a tabulating operation, or in case a tabulator-key 50 is erroneously or accidentally actuated to cause the extension 60 to start the carriage-returning mechanism, it will be seen that the carriage-returning operation will be held in abeyance, since the arm 150, 110 which is actuated by the depression of a tabulator-key 50, is taking up all the lost-motion between the pendants 128, 133, thereby preventing the vertical bar 132 of the carriage-returning mechanism from entering between said pendant until the end 115 of the return stroke of the tabulator-key 50, at which time its associated stop 53 will be out of colliding position with the dogs 54 at the rear of the carriage. 120

The machine, herein illustrated, is also provided with means for returning the carriage 17 from any point in its travel between the right and left marginal stops.

For this purpose, there is provided a 130

5 manual carriage-return-key 156 (Fig. 1) mounted on a bell-crank 157, normally held in ineffective position by a spring 158, co-acting with a one-way pawl 159 (Figs. 1 and 4) to release the latch 68 of the carriage-returning mechanism and thereby close the switch 108 and clutch 73, to return the carriage 17 and the totalizers 44 thereon.

10 It will be seen that the depression of this manual carriage-return-key 156 cannot be effective to return the carriage during the depression of a numeral key 10, or during the depression of a tabulator-key 50, thereby avoiding collision of the teeth of the computing wheels 45 with the master-wheel 42, or the collision of the dogs 54 at the rear of the carriage 17 with the tabulator-stops 53, since the vertical bar 132 of the carriage-returning mechanism, co-acting with the pendants 128, 133, cannot be raised, thereby holding the carriage-returning mechanism in abeyance until all of the numeral keys 10 and decimal-tabulator-keys 50 are in their normal positions, at which time there will be no obstructions in the path of the computing wheels 45 and the tabulator dogs 54 during the return of the typewriter carriage and the totalizers.

15 In case a totalizer 44 or the left marginal stop 30 is erroneously placed, so that the carriage extension 60 reaches the left marginal stop to actuate the carriage-returning mechanism before the computing wheel 45 and the dial wheel 144 of lowest denomination reaches the computing point or master-wheel 42, collision of the teeth of the computing wheels and master-wheel will be prevented, since the pendants 128, 133, associated with the vertical bar 132, which lock 20 the carriage-returning mechanism against actuation, will be effective to prevent a carriage-returning operation under these conditions, as well as at the end of a computation. This is also true in case the manual 25 carriage-returning key 156 is actuated during a computing operation before the computing wheel 45 of lowest denomination passes the master-wheel.

30 It will be noted that when a computation is taking place in lowest denomination, which includes a carry-over operation, prior to a carriage-returning operation, said carry-over operation will be completed before the carriage-returning operation takes place, 35 since said carry-over operation is completed before the end of the return stroke of a numeral key 10, prior to which the carriage 17 cannot be automatically returned, thereby avoiding collision of the teeth of the 40 computing wheels 45 with the teeth of the displaced carry-over wheels, thus avoiding wreckage of the machine. The carriage-returning operation will be prevented under these conditions in the same manner in case 45 the manual carriage-returning key 156 is

actuated during a carry-over operation in any denominational position of the totalizer.

45 The computing wheels 45 and dial wheels 144 (Figs. 1 and 4) are arranged at letter-space intervals and in groups; a single letter-space 162 (Fig. 4) being usually provided between said groups, in which a punctuation mark may be typed upon the work-sheet.

50 To prevent the operative from inadvertently actuating a numeral key when a punctuation space 162 is at the master-wheel 42, and thereby typewriting a digit, which will not be computed, there is provided a mechanism to lock the numeral keys when a punctuation space 162 is at the master-wheel 42.

55 The mechanism for locking the numeral keys in a punctuation space includes tappets 163 (Figs. 1 and 4) fixed at the rear of the totalizers 44, one for each punctuation space 162. The tappets 163 are placed to engage a cam 164 on a horizontal lever 165 fulcrumed on the framework of the machine, during the movement of the carriage 17 and the totalizer 44. When a numeral key 10 is actuated in the lowest denomination of a group of dial wheels 144, the associated tappet 163 will lie adjacent to and at the right of said cam 164, which, at the completion of the computing action, will be swung and held rearwardly by said tappet 163, thereby swinging the other end of said lever 165 forwardly to swing a bell-crank 168, pivoted on the framework of the machine, to raise a rearwardly-extending arm 169 of said bell-crank 168 which has a pin 170 fast thereon, to the free end of which is connected a spring 171, the other end of which is connected to a pin 172 fast on the vertically-disposed bar 132 of the carriage-returning mechanism, to raise said bar through the intermediary of said spring, so that it will pass between its adjacent pendants 128, 133, thereby taking up all the lost-motion between all the pendants, to prevent the passage of any other member between any of said pendants, and thus prevent the depression of any numeral key.

60 At the actuation of a character key 11, to print a punctuation mark at said punctuation space 162, or at the actuation of the usual space-key 173, the carriage 17 will move an additional letter-space and move said tappet 163, which is in engagement with the cam 164 of the lever 165, out of engagement with said cam 164, thereby permitting said lever and connected parts, including the vertically-disposed bar 132, to return to their normal positions, in which a numeral key may be depressed and computation continued.

65 The combination is such that, in case the escapement mechanism 22 is effective to let-letter-space the carriage 17 before an actuated

75

130

numeral key is returned to its normal position, when computing in lowest denomination of a group of dial wheels, said carriage and totalizer 44 thereon will not be prevented from moving in a letter-feeding direction. The typewriter carriage letter-feeds at the up-stroke of a numeral key when the associated plunger 125 lies between its pendants 128. At this time the vertical bar 132 cannot be actuated, but the carriage 17 will be free to move in letter-feeding direction, since said bar 132 does not positively hold the bell-crank 168 and the horizontal lever 165 connected therewith, the spring 171 providing a flexible connection, thus permitting said horizontal lever 165 and bell-crank 168 to be actuated as a tappet 163 passes over the cam 164 of the lever 165, while the vertical bar 132 remains immovable. At the end of the up-stroke of the numeral key, its plunger 125 will move out of engagement with its pendants 128, thereby permitting the spring 171 to draw the vertical bar 132 upwardly so that it may pass between the pendants 128, 133, to lock the numeral keys against actuation when a punctuation space 162 is at the computing point.

To permit the vertically-disposed bar 132 to rise, without disturbing the carriage-returning mechanism, when actuated by a tappet 163 at a punctuation space, the slot 139 at the central portion of said bar is made of sufficient length to enable said bar to rise without swinging the lever 136 which connects said bar with the rock-shaft 71 of the carriage-returning mechanism.

It will be noted that economy of production is effected by employing a single vertically-disposed bar 132 for locking the numeral keys and the decimal-tabulator-keys, during a carriage-returning operation; for locking the carriage-returning mechanism during the actuation of the numeral keys or the decimal-tabulator-keys; and for locking the numeral keys and decimal-tabulator keys when a punctuation space is at the computing point.

Said vertically-disposed bar 132, when actuated for any purpose herein described, is returned to its normal position by a spring 176 (Figs. 1 and 4) formed so as to be overcome by the spring 67 attached to the thrust bar 65 of the carriage-returning mechanism and by the spring 171 connected with the mechanism for locking the numeral keys when a punctuation space is at the computing point.

Variations may be resorted to within the scope of the invention and portions of the improvements may be used without others.

Having thus described my invention, I claim:

1. The combination with a traveling carriage, of type-keys, means operated by the

keys to cause letter-feeding movements of said carriage, means rendered effective by said carriage for returning said carriage to its initial position, and means for preventing the return of said carriage during the actuation of said keys.

2. The combination with a traveling carriage, of type-keys, means operated by the keys to cause letter-feeding movements of said carriage, means rendered effective by said carriage for automatically returning said carriage, and means for preventing the urging of said carriage in a return direction by said returning means when a key is in actuated position.

3. In a combined typewriting and computing machine, the combination with a traveling carriage, of numeral keys, means operated by the keys to cause letter-feeding movements of said carriage, motor-driven means controlled by said carriage for automatically returning said carriage, and means for preventing the control of said motor-driven means by said carriage when a numeral key is in actuated position.

4. In a combined typewriting and computing machine, the combination with a traveling carriage, of numeral keys, means operated by the keys to cause letter-feeding movements of said carriage, means for automatically returning said carriage to its initial position, and means controlled by said numeral keys for preventing the returning means from urging the return of said carriage when a numeral key is in actuated position.

5. In a combined typewriting and computing machine, the combination with a traveling carriage, of numeral keys, means operated by the keys to cause letter-feeding movements of said carriage, motor means for automatically returning said carriage to its initial position, mechanism for preventing the simultaneous actuation of two or more numeral keys, and means co-operating with said mechanism for preventing said motor means from urging said carriage in a return direction when a numeral key is in actuated position.

6. In a combined typewriting and computing machine, the combination with a traveling carriage, of numeral keys, means operated by the keys to cause letter-feeding movements of said carriage, an electric motor for driving said carriage in return direction, a normally-open switch in the circuit of said motor, means for closing said switch, and means for locking said switch against actuation when a numeral key is in actuated position.

7. In a combined typewriting and computing machine, the combination with a traveling carriage, of numeral keys, means operated by the keys to cause letter-feeding movements of said carriage, a motor for

driving said carriage in return direction, a normally-open switch for starting said motor, means controlled by said carriage for closing said switch, and means for locking said switch

5 against actuation when a numeral key is in actuated position.

8. In a combined typewriting and computing machine, the combination with a traveling carriage, of numeral keys, means operated by the keys to cause letter-feeding movements of said carriage, a motor-driven mechanism for returning said carriage, a normally-open clutch between said motor-driven mechanism and said carriage for actively connecting said carriage and said mechanism, means for closing said clutch, and means for locking said clutch against actuation when a numeral key is in actuated position.

20 9. In a combined typewriting and computing machine, the combination with a traveling carriage, of numeral keys, means operated by the keys to cause letter-feeding movements of said carriage, a motor-driven

25 mechanism for driving said carriage in return direction, a normally-open clutch between said motor-driven mechanism and said carriage for actively connecting said carriage and said mechanism, means controlled by said carriage for closing said clutch, and means for locking said clutch against closing when a numeral key is in actuated position.

10. In a combined typewriting and computing machine, the combination with a traveling carriage, of numeral keys, means operated by the keys to cause letter-feeding movements of said carriage, a motor-driven mechanism for driving said carriage in return direction, a normally-open clutch for actively connecting said motor-driven mechanism and said carriage, means controlled by said carriage for closing said clutch, mechanism for preventing the simultaneous actuation of two or more numeral keys, and means coöperating with said last-named mechanism for preventing the closing of said clutch when a numeral key is in actuated position.

50 11. In a combined typewriting and computing machine, the combination with a traveling carriage, of numeral keys, means operated by the keys to cause letter-feeding movements of said carriage, an electric motor for driving said carriage in return direction, a normally-open switch for closing the circuit through said motor, means controlled by said carriage for closing said switch, mechanism for preventing the simultaneous

55 actuation of two or more numeral keys, and means coöperating with said mechanism for preventing the closing of said switch when a numeral key is in actuated position.

60 12. In a combined typewriting and com-

puting machine, the combination with a traveling carriage, of keys, means operated by the keys to cause letter-feeding movements of said carriage, means for automatically returning said carriage to its initial position at the end of a key actuation, means controlled by said carriage for initiating said carriage-returning operation, and means for holding said carriage-returning means in abeyance until the end of said key

70

75

13. In a combined typewriting and computing machine, the combination with a traveling carriage, of numeral keys, means operated by the keys to cause letter-feeding movements of said carriage, means controlled by the carriage for automatically returning said carriage to its initial position, mechanism for preventing the simultaneous actuation of two or more numeral keys, and a member connected with said carriage-returning means, and coöperating with said mechanism, for locking said carriage-returning means against actuation.

14. In a combined typewriting and computing machine, the combination with a traveling carriage, of numeral keys, for causing letter-feeding movements of said carriage when actuated, a motor-driven mechanism for driving said carriage in return direction, a normally-open clutch for actively connecting said motor-driven mechanism with the carriage, means controlled by the carriage for closing said clutch, mechanism for preventing the simultaneous actuation of two or more numeral keys, and a member connected with said clutch-closing means, and coöperating with said last-named mechanism, for preventing the closing of said clutch when a numeral key is in actuated position.

15. In a combined typewriting and computing machine, the combination with a traveling carriage, of numeral keys, for causing letter-feeding movements of said carriage when actuated, an electric motor for driving said carriage in return direction, a normally-open switch for closing the circuit through said motor, means controlled by said carriage for closing said switch, mechanism for preventing the simultaneous actuation of two or more numeral keys, and a member connected with said switch-closing means, and coöperating with said mechanism, for locking said switch against actuation when a numeral key is in actuated position.

16. In a combined typewriting and computing machine, the combination with a traveling carriage, of numeral keys, for causing letter-feeding movements of said carriage when actuated, a motor-driven mechanism for driving said carriage in return direction, a normally-open clutch for actively connecting said motor-driven mech-

- anism with said carriage, an electric motor for driving said motor-driven mechanism, a normally-open switch for closing the circuit through said motor, means controlled by 5 said carriage for closing said switch and clutch, mechanism for preventing the simultaneous actuation of two or more numeral keys, and a member connected with said switch and clutch-closing means, and co-operating with said last-named mechanism, 10 for locking said switch and clutch against actuation.
17. In a combined typewriting and computing machine, the combination with a traveling carriage, of keys for causing letter-feeding movements of said carriage when actuated, means for returning said carriage to its initial position at the end of a key-actuation, manually-operable means 20 for initiating said carriage-returning operation, and means for holding said carriage-returning means in abeyance until the end of said key-actuation.
18. In a combined typewriting and computing machine, the combination with a traveling carriage, of numeral keys, means operated by the keys to cause letter-feeding movements of said carriage, a motor-driven mechanism for driving said carriage 25 in return direction, a normally-open clutch for actively connecting said motor-driven mechanism with the carriage, an electric motor for driving said motor-driven mechanism, a normally-open switch for closing 30 the circuit through said motor, means controlled by a key for closing said switch and clutch, mechanism for preventing the simultaneous actuation of two or more numeral keys, and a member connected with said switch and clutch-closing means, and co-operating with said last-named mechanism, 35 for locking said switch and clutch against actuation when a numeral key is in actuated position.
19. In a combined typewriting and computing machine, the combination with a traveling carriage, of numeral keys, means operated by the keys to cause letter-feeding movements of said carriage, means for automatically returning said carriage to its 40 initial position, a normally-effective latch for holding said carriage-returning means in ineffective position, means controlled by said carriage for moving said latch to ineffective position, and means for holding the carriage-returning means in ineffective position during the actuation of a numeral key when said latch is in ineffective position.
20. In a combined typewriting and computing machine, the combination with a traveling carriage, of a totalizer traveling with said carriage, and comprising computing wheels arranged in groups to provide punctuation spaces, a master wheel 45 cooperating with said computing wheels, means for returning said carriage to its initial position, and means for preventing the return of said carriage when said master wheel is opposite one of said punctuation spaces.
21. In a combined typewriting and computing machine, the combination with a traveling carriage, of a computing element traveling with said carriage, a substantially stationary computing element co-operating 50 with said traveling computing element, motor means for returning said carriage to its initial position, and means for preventing the urging of said carriage in a return direction, by said returning means, during a computing action.
22. The combination with a traveling carriage, of type-keys, means operated by the keys to cause letter-feeding movements of said carriage, carriage-returning means normally disconnected from said carriage, controlling means to establish a connection between said carriage and said carriage-returning means, and means to prevent said controlling means from establishing such connection between said carriage and said carriage-returning means during the actuation 55 of said keys.
23. The combination with a traveling carriage, of type-keys, means operated by the keys to cause letter-feeding movements of said carriage, motor means for returning said carriage, normally disconnected from said carriage, controlling means to establish a connection between said returning means 60 and said carriage, and means to prevent the establishment of such connections when a key is in actuated position.
24. The combination with a traveling carriage, of numeral keys, means operated by the keys to cause letter-feeding movements of said carriage, motor driven means controlled by said carriage for automatically returning the same, and means to prevent said motor-driven means from urging said carriage in the return direction when a numeral key is in actuated position.
25. The combination with a traveling carriage, of numeral keys, means operated by the keys to cause letter-feeding movements of said carriage, means for automatically returning said carriage to its initial position, carriage-controlled means tending to render said returning means effective, and means controlled by said numeral keys to prevent 110 said carriage-controlled means from rendering said returning means effective when a numeral key is in actuated position.
26. In a combined typewriting and computing machine, the combination with a traveling carriage, of a computing element traveling with said carriage, a substantially stationary computing element co-operating 115 with said traveling computing element, means for returning said carriage to its ini- 120 125 130

tial position, mechanism controlled by said carriage for initiating the carriage-returning action during a computing action, and means for holding said carriage-returning 5 means in abeyance until the end of said computing action.

27. In a combined typewriting and computing machine, the combination with a traveling carriage, of a computing wheel traveling with said carriage, a master wheel coöperating with said computing wheel, means for automatically actuating said carriage when said wheels are in meshing position, mechanism on said carriage for initiating 10 said carriage actuating operation, means for preventing said automatic carriage-actuation when said wheels are in colliding position, and means for holding said automatic carriage-actuating means in abeyance until 15 said wheels are in said meshing position.

28. The combination with a traveling carriage, of numeral keys, means operated by said keys to cause letter-feeding movements of said carriage, motor means for driving 25 said carriage in the return direction, a controlling device for starting said motor means, and means to prevent the starting of said motor means by said controlling device when a numeral key is in actuated position.

29. In a combined typewriting and computing machine, the combination with a traveling carriage, of a computing element traveling with said carriage, a substantially-stationary computing element coöperating 35 with said traveling element, numeral keys controlling said computing elements, mechanism for preventing simultaneous actuation of two or more numeral keys, means for returning said carriage to its initial position, 40 and a member connected with said carriage-returning means, and coöperating with said mechanism, for locking said carriage-returning means against actuation during a computing action.

30. The combination with a traveling carriage, of numeral keys, numeral-key-actuated means to cause letter-feeding movements of said carriage, motor mechanism for returning said carriage, a normally open connecting device between said motor mechanism and said carriage, means for rendering said connecting device effective, and means for preventing said connecting device from being rendered effective during the actuation 55 of a numeral key.

31. In a combined typewriting and computing machine, the combination with a traveling carriage, of a totalizer traveling with said carriage, a master wheel coöperating 60 with said totalizer, motor-driven means for returning said carriage to its initial position, an electric switch for closing the circuit through the motor, and means for locking said switch against actuation when said 65 master wheel is in an abnormal position.

32. In a combined typewriting and computing machine, the combination with a traveling carriage, of a totalizer traveling with said carriage, a master wheel coöperating with said totalizer, a motor-driven mechanism for returning said carriage to its initial position, a normally-open clutch for actively connecting said mechanism with said carriage, and means for locking said clutch against closing when said 70 master wheel is in an abnormal position.

33. In a combined typewriting and computing machine, the combination with a traveling carriage, of a computing element traveling with said carriage, a substantially-stationary computing element coöperating 80 with said traveling computing element, a motor-driven mechanism for returning said carriage to its initial position, an electric switch for closing the circuit through the 85 motor, a normally-open clutch for actively connecting said mechanism with said carriage, and a single means for simultaneously locking said switch and clutch against actuation during a computing action. 90

34. In a combined typewriting and computing machine, the combination with a traveling carriage, of a totalizer traveling with said carriage, a master wheel coöperating with said totalizer, normally-ineffective 95 means for returning said carriage to its initial position, means for locking said carriage-returning means in ineffective position, means controlled by the carriage for releasing said carriage-returning means, and 100 means for rendering said releasing means ineffective when said master wheel is in an abnormal position.

35. In a combined typewriting and computing machine, the combination with a traveling carriage, of a computing element traveling with said carriage, a substantially-stationary computing element coöperating with said traveling element, numeral keys controlling said computing elements, mechanism for preventing the simultaneous actuation of two or more numeral keys, a normally-ineffective means for returning said carriage to its initial position, a latch for locking said carriage-returning means in ineffective position, means controlled by the carriage for releasing said latch, and means 110 coöperating with said mechanism for rendering said released latch ineffective when said stationary computing element is in an abnormal position. 115

36. In a combined typewriting and computing machine, the combination with a traveling carriage, of a computing element traveling with said carriage, a substantially-stationary computing element coöperating 125 with said traveling computing element, motor-driven means for returning said carriage to its initial position, an electric switch for closing the circuit through the motor, and 130

- means for locking said switch against actuation during a computing action.
37. In a combined typewriting and computing machine, the combination with a traveling carriage, of a computing element traveling with said carriage, a substantially-stationary computing element coöperating with said traveling computing element, a motor-driven mechanism for returning said carriage to its initial position, a normally-open clutch for actively connecting said mechanism with the carriage, and means for locking said clutch against closing during a computing action.
38. In a combined typewriting and computing machine, the combination with a carriage, of means for causing jump movements of said carriage, means for returning said carriage to its initial position, and means for preventing the returning means from urging said carriage in a return direction during the actuation of said means for causing said jump movements.
39. In a combined typewriting and computing machine, the combination with a carriage, of means for positioning said carriage denominational prior to a computing action, means for returning said carriage to its initial position, and means for preventing the return of said carriage during the actuation of said denominational-positioning means.
40. In a combined typewriting and computing machine, the combination with a carriage, of a decimal-tabulating mechanism for said carriage, means for automatically returning said carriage to its initial position, and means for preventing the return of said carriage during the actuation of said decimal-tabulating mechanism.
41. In a combined typewriting and computing machine, the combination with a carriage, of a decimal-tabulating mechanism for said carriage, a plurality of keys for actuating said decimal-tabulating mechanism, means for automatically returning said carriage to its initial position, and means for preventing the return of said carriage during the actuation of any one of said keys.
42. In a combined typewriting and computing machine, the combination with a carriage, of a decimal-tabulating mechanism for said carriage, a plurality of keys whereby said decimal-tabulating mechanism may be actuated, means for automatically returning said carriage to its initial position, and means for preventing the return of said carriage when a key is in actuated position.
43. In a combined typewriting and computing machine, the combination with a traveling carriage, of decimal-tabulating mechanism for said carriage including a plurality of denominational stops, keys for moving said stops into the path of dogs on said carriage, means for automatically returning said carriage to its initial position, a switch actuable for closing the circuit through the motor, and means for preventing the actuation of said switch when a stop is in the path of a dog.
44. In a combined typewriting and computing machine, the combination with a carriage, of a decimal-tabulating mechanism for said carriage, means for automatically returning said carriage to its initial position, means on said carriage for initiating said carriage-returning operation when said decimal-tabulating mechanism is actuated, and means for holding said carriage-returning means in abeyance until the end of said decimal-tabulating action.
45. In a combined typewriting and computing machine, the combination with a carriage, of a decimal-tabulating mechanism for said carriage, a normally-inoperative motor-driven mechanism for returning said carriage to its initial position, a switch for closing the electric circuit through the motor, and means for preventing the closing of said switch during the actuation of said decimal-tabulating mechanism.
46. In a combined typewriting and computing machine, the combination with a carriage, of means for positioning said carriage denominational, a manually-operable key for causing a return movement of said carriage to its initial position, and means for preventing the return of said carriage when said key is operated during the actuation of said denominational-positioning means.
47. In a combined typewriting and computing machine, the combination with a carriage, of a decimal-tabulating mechanism for said carriage, keys for actuating said decimal-tabulating mechanism, a computing mechanism, numeral keys controlling said computing mechanism, mechanism for preventing the simultaneous actuation of a numeral key and a decimal-tabulating key, means for automatically returning said carriage to its initial position, and means cooperating with said last-named mechanism for preventing the return of said carriage during the actuation of any one of said keys.
48. In a combined typewriting and computing machine, the combination with a traveling carriage, of decimal-tabulating mechanism for said carriage including a plurality of substantially-stationary denominational stops, keys for moving said stops into the path of dogs on said carriage, a motor-driven mechanism for automatically returning said carriage to its initial position, a switch actuatable for closing the circuit through the motor, and means for preventing the actuation of said switch when a stop is in the path of a dog.
49. In a combined typewriting and com-

- puting machine, the combination with a traveling carriage, of decimal-tabulating mechanism for said carriage including a plurality of substantially-stationary denominational stops, means for moving said stops into the path of dogs on said carriage, a motor-driven mechanism for automatically returning said carriage to its initial position, a normally-open clutch for actively connecting said last-named mechanism with said carriage, and means for preventing the closing of said clutch when a stop is in the path of a dog. 54. In a combined typewriting and computing machine, the combination with a carriage, of a decimal-tabulating mechanism for said carriage, a normally-ineffective motor-driven mechanism for returning said carriage to its initial position, a normally-open clutch for actively connecting said last-named mechanism with said carriage, and means for preventing the closing of said clutch during the actuation of said decimal-tabulating mechanism. 55. In a combined typewriting and computing machine, the combination with a carriage, of type keys, means operated by the keys to cause letter-feeding movements of said carriage, means rendered effective by said carriage for returning said carriage to its initial position, mechanism for preventing the simultaneous actuation of two or more of said keys, and means for rendering said preventing mechanism effective to lock all of said keys against actuation during the return movement of the carriage. 56. In a combined typewriting and computing machine, the combination with a carriage, of numeral keys, means operated by the keys to cause letter-feeding movements of said carriage, means rendered effective by said carriage for automatically returning said carriage to its initial position, mechanism for preventing the simultaneous actuation of two or more of said keys, means for rendering said preventing mechanism effective to lock all of said keys against actuation during the return movement of said carriage, and means for unlocking said keys when said carriage reaches its initial position. 57. In a combined typewriting and computing machine, the combination with a carriage, of numeral keys, means operated by the keys to cause letter-feeding movements of said carriage, an electric motor-driven mechanism for returning said carriage to its initial position, a switch placed in the circuit of the motor, means controlled by said carriage for closing said switch at a letter-feeding movement of said carriage, means for opening said switch when the carriage reaches its initial position, mechanism for preventing the simultaneous actuation of two or more of said keys, and means for effecting a locking of all the numeral keys by said preventing mechanism when the switch is closed. 58. In a combined typewriting and computing machine, the combination with a carriage, of numeral keys, means operated by the keys to cause letter-feeding movements of said carriage, an electric motor-driven mechanism, including a normally-open clutch, for returning said carriage to its initial position, means controlled by said carriage for closing said clutch at a letter-feeding movement of said carriage, means for opening said clutch when the carriage reaches its initial position, mechanism for preventing the simultaneous actuation of two or more of said keys, and means whereby said preventing mechanism will be rendered effective to lock said numeral keys against actuation when said clutch is closed. 59. In a combined typewriting and computing machine, the combination with a carriage, of numeral keys, means operated by the keys to cause letter-feeding movements of said carriage, an electric motor-driven mechanism, including a normally-open clutch, for returning said carriage to its initial position, a switch placed in the circuit of the motor, means controlled by the carriage for simultaneously closing said switch and clutch at a letter-feeding movement of the carriage, means for simultaneously opening said switch and clutch when the carriage reaches its initial position, mechanism for preventing the simultaneous actuation of two or more of said keys, and means whereby said preventing mechanism will be rendered effective to lock the numeral keys against actuation when said switch and clutch are closed. 60. The combination with a traveling carriage, of numeral keys, numeral-key-actuated means for causing letter-feed movements of said carriage, motor mechanism for driving said carriage in the return direction, a normally ineffective device for connecting said motor mechanism with said carriage, a controlling device for rendering said motor mechanism effective, carriage-controlled means to render said connecting device effective and to actuate said controlling device to render said motor mechanism effective, and means to prevent said connecting device and said motor mechanism from being rendered effective during the actuation of a numeral key. 61. In a combined typewriting and computing machine, the combination with a traveling carriage, of a computing mechanism including numeral keys and a master wheel, means for causing a letter-feeding movement of said carriage, means rendered effective by said carriage for returning said carriage to its initial position, mechanism for preventing the simultaneous actuation of two or more of said keys, and means for

- of two or more of said keys, and means, effective through said preventing mechanism, to prevent actuation of said computing mechanism by the numeral keys during the 5 return movement of said carriage.
58. In a combined typewriting and computing machine, the combination with a carriage, of numeral keys, key-operated means to cause letter-feeding movements of the 10 carriage, carriage-return means rendered effective by said carriage when it reaches a predetermined position, mechanism whereby actuation of one of said numeral keys will effect locking of the others, and means effective during a carriage-return movement to modify the operation of the locking mechanism, so as to lock all of said numeral keys thereby.
59. In a combined typewriting and computing machine, the combination with a carriage, of numeral keys, key-operated means to cause letter-feeding movements of the carriage, automatic carriage-return means, a locking device normally effective upon actuation of one of said numeral keys to lock the others, means whereby said device will be caused to lock all of said numeral keys during the return movement of the carriage, and means for restoring said locking device 25 to its normal condition when the carriage reaches a predetermined position in its return movement.
60. In a combined typewriting and computing machine, the combination with a carriage, of numeral keys, means operated by the keys to cause letter-feeding movements of said carriage, means for automatically returning the carriage to its initial position, mechanism whereby actuation of any one of 30 said numeral keys will effect a locking of the others, means actuated by said carriage-returning means for rendering said mechanism effective for locking all of said keys against actuation during the return of said carriage, and means for unlocking said keys when said carriage reaches its initial position.
61. In a combined typewriting and computing machine, the combination with a carriage, of numeral keys, numeral-key-actuated means to cause letter-feeding movements of the carriage, normally ineffective carriage-returning mechanism, a controlling device for said carriage-returning mechanism 35 normally urged to render said returning mechanism effective, a latch for restraining said controlling device, means controlled by the carriage for tripping said latch to release the controlling device, means for releasing said controlling device to the control of said latch when the carriage reaches the end of its return movement, and means whereby effective movement of said controlling device will be delayed, in case said latch is tripped while a numeral key is in 40 depressed position, until the numeral key is restored to its normal position.
62. In a combined typewriting and computing machine, the combination with a carriage, of numeral keys, means operated by the keys to cause letter-feeding movements of said carriage, a normally-ineffective means for automatically returning said carriage to its initial position, a latch for locking said carriage-returning means in normal position, means controlled by the carriage for tripping said latch to move the carriage-returning means to effective position, means for holding said latch in actuated position, means for returning said latch to effective position when said carriage reaches its initial position, and means whereby, in case a numeral key is in actuated position when said latch is tripped, the carriage-returning means will be maintained in ineffective condition until the numeral key is returned to normal position.
63. In a combined typewriting and computing machine, the combination with a carriage, of means for controlling the movement of said carriage comprising numeral keys, a tabulator keys and a carriage-return mechanism thrown into and out of action by the carriage, and a locking device common to said keys and return mechanism ineffective to prevent actuation of said keys one at a time, or the throwing into action of said return mechanism when said keys are in normal position, but effective when any one of said keys is actuated to lock all of the 100 other keys and to prevent throwing into action of said return mechanism, and effective when said return mechanism has been thrown into action to lock all of said keys.
64. In a combined typewriting and computing machine, the combination with a traveling carriage, of a totalizer on said carriage, a master wheel co-operating with said totalizer, numeral keys controlling the master wheel, mechanism whereby actuation of any one of said numeral keys will lock the other numeral keys, means for denominational positioning said totalizer relatively to the master wheel, means for returning said carriage to its initial position, and means controlled by said carriage-returning means to render said mechanism effective to prevent the actuation of said denominational positioning means during the return movement of the carriage.
65. In a combined typewriting and computing machine, the combination with a traveling carriage, of a totalizer on said carriage, a master wheel co-operating with said totalizer, numeral keys controlling the master wheel, mechanism for preventing the simultaneous actuation of two or more numeral keys, means for denominational positioning said totalizer relatively to the master wheel, means for returning said carriage to its initial position, and means controlled by said carriage-returning means to render said mechanism effective to prevent the actuation of said denominational positioning means during the return movement of the carriage.

- riage to its initial position, a member controlled by said carriage-returning means, and coöperating with said mechanism, effective for preventing the actuation of said 5 denominational positioning means; during the return movement of the carriage, and means for holding said member in effective position during said returning movement of the carriage.
- 10 66. In a combined typewriting and computing machine, the combination with a traveling carriage, of a traveling computing element on said carriage, a non-traveling computing element coöperating with said 15 traveling computing element, tabulating means for denominational positioning said traveling computing element relatively to the non-traveling computing element, means for returning said carriage to its initial position, and a single means for preventing the actuation of said tabulating means and the actuation of the computing elements during the return movement of the carriage.
- 20 67. In a combined typewriting and computing machine, the combination with a traveling carriage, of groups of computing wheels on said carriage, spaces between said groups of wheels, numeral keys, means operated by the keys to actuate said wheels and the carriage, means for returning said carriage to its initial position, and a single member effective to lock the numeral keys when a space is at a computing point and during the return of said carriage.
- 25 68. In a combined typewriting and computing machine, the combination with a traveling carriage, of groups of computing wheels on said carriage, spaces between said groups of wheels, numeral keys, means operated by the keys to actuate said wheels and the carriage, means for returning said carriage to its initial position, a single locking member effective on the numeral keys when a space is at the computing point and 30 during the return of said carriage, and means for rendering said locking member ineffective when a computing wheel is at the computing point.
- 35 69. In a combined typewriting and computing machine, the combination with a traveling carriage, of groups of computing wheels on said carriage, punctuation spaces between said groups of wheels, numeral keys, means operated by the keys to actuate said wheels and the carriage, means for returning said carriage to its initial position, a single locking means for said numeral keys effective when any one of said spaces is at the computing point and during the 40 return of said carriage, and means for rendering said key-locking means ineffective when the carriage reaches its initial position.
- 45 70. In a combined typewriting and computing machine, the combination with a traveling carriage, of a totalizer on said carriage including groups of computing wheels, punctuation spaces between said groups of wheels, numeral keys, means operated by the keys to actuate said wheels and the carriage, means for returning said carriage to its initial position, mechanism controlled by the totalizer for locking said keys against actuation when a punctuation space reaches the computing point during a letter-feeding movement of the carriage, and means for rendering said mechanism uncontrollable by the totalizer during a return movement of said carriage.
- 50 71. In a combined typewriting and computing machine, the combination with a traveling carriage, of a totalizer on said carriage including groups of computing wheels, punctuation spaces between said groups of wheels, numeral keys, means operated by the keys to actuate said wheels and the carriage, means for returning said carriage to its initial position, cams on said totalizer placed in accord with said punctuation spaces, mechanism controlled by said cams for locking said keys against actuation when a space is at the computing point, and means to prevent actuation of said mechanism by said cams during a return movement of said carriage.
- 55 72. In a combined typewriting and computing machine, the combination with a traveling carriage, of a totalizer on said carriage including groups of computing wheels, punctuation spaces between said groups of wheels, numeral keys, means operated by the keys to actuate said wheels and the carriage, means for returning said carriage to its initial position, mechanism for preventing a simultaneous actuation of two or more 60 numeral keys, and means controlled by the totalizer coöperating with said mechanism for preventing the actuation of any numeral key when a punctuation space is at the computing point.
- 65 73. In a combined typewriting and computing machine, the combination with a traveling carriage, of a totalizer on said carriage including groups of computing wheels, punctuation spaces between said groups of wheels, numeral keys, means operated by a single actuation of the keys to actuate said wheels and the carriage, means for returning the carriage to its initial position, mechanism for preventing a simultaneous actuation of two or more 70 numeral keys, a member controlled by said carriage-returning means, and coöperating with said mechanism, for locking the keys against actuation during a return movement of the carriage, cams on 75 said totalizer placed in accord with said punctuation spaces, and a lever controlled by the cams and actively connected with said member for locking said keys against actuation when a space is at the computing point,

for preventing control of said lever by said cams being prevented during a return movement of said carriage.

74. In a combined typewriting and computing machine, the combination with a traveling carriage, of a totalizer on said carriage including groups of dial wheels, punctuation spaces between said groups of wheels, numeral keys, means operated by a single actuation of the keys to actuate said wheels and the carriage, means for returning said carriage to its initial position, cams on said totalizer placed in accord with said punctuation spaces, a lever controlled by the cams operable for locking said keys against actuation when a punctuation space reaches the computing point at a letter-feeding movement of the carriage, and means for rendering said lever uncontrollable by the cams during the return movement of said carriage.

75. In a combined typewriting and computing machine, the combination with a traveling carriage, of a totalizer on said carriage including groups of dial wheels, punctuation spaces between said groups of wheels, numeral keys, means operated by a single actuation of the keys to actuate said wheels and the carriage, means for returning said carriage to its initial position, cams on said totalizer placed in accord with said punctuation spaces, a lever normally in the path of said cams operable by said cams for locking said keys against actuation when a punctuation space reaches the computing point at a letter-feeding movement of the carriage, and means for moving said lever out of the path of said cams during a return movement of said carriage.

40 76. In a combined typewriting and computing machine, the combination with a carriage, of means for moving said carriage in letter-feeding direction, means for automatically returning said carriage to its initial position, an electric motor for driving said carriage in return direction, and a switch to close the electric circuit through the motor, said switch being loosely and detachably connected with said automatic carriage-returning means.

55 77. In a combined typewriting and computing machine, the combination with a carriage, of means for moving said carriage in letter-feeding direction, means for automatically returning said carriage to its initial position, an electric motor for driving said carriage in a return direction, and a switch to close the electric circuit through the motor, said switch being loosely and detachably connected to said automatic carriage-returning means and accessibly placed without the machine.

60 78. In a combined typewriting and computing machine, the combination with a car-

riage, of means for moving said carriage in letter-feeding direction, means for automatically returning said carriage to its initial position, an electric motor for driving said carriage in return direction, a switch including terminals to close the electric circuit through the motor, said switch being loosely and detachably connected to said automatic carriage-returning means, and a spring urging said terminals into contact, said spring being normally held in abeyance by said carriage-returning means.

79. In a combined typewriting and computing machine, the combination with a carriage, of means for moving said carriage in letter-feeding direction, means permanently attached to the machine for automatically returning said carriage to its initial position, an electric motor for driving said carriage in a return direction, and a switch to close the electric circuit through the motor, said switch being loosely connected to said carriage-returning means and detachably connected to the machine.

80. In a combined typewriting and computing machine, the combination with a traveling carriage, of numeral keys, means operated by the numeral keys for causing letter-feeding movements of said carriage, mechanism rendered effective by said carriage for causing a return movement of said carriage, and means whereby actuation of said numeral keys will prevent actuation of said carriage-returning mechanism, and actuation of the latter will prevent actuation of the former.

100 81. In a combined typewriting and computing machine, the combination with a traveling carriage, of numeral keys, means operated by the numeral keys for causing letter-feeding movements of said carriage, tabulator keys, means operated by the tabulator keys for causing jump movements of said carriage, mechanism for causing a return movement of said carriage, and means whereby actuation of any one of said numeral keys will prevent actuation of said carriage-returning mechanism, and actuation of said carriage-returning mechanism will prevent actuation of any of said numeral keys.

115 82. In a combined typewriting and computing machine, the combination with a traveling carriage, of a computing mechanism traveling with said carriage, a non-traveling computing mechanism including numeral keys and co-operating with said traveling computing mechanism, mechanism rendered effective by said carriage for causing a return movement of said carriage, and means whereby actuation of either said non-traveling computing mechanism or said carriage-returning mechanism will prevent actuation of the other.

83. In a combined typewriting and computing machine, the combination with a carriage, of tabulating means for positioning said carriage, means, including a manually operable key, for causing a return movement of said carriage to its initial position, and means for preventing the return of said carriage when said key is operated during the actuation of said tabulating means.

HENRY L. PITMAN.
